UNITED STATES PATENT OFFICE.

WILLIAM F. PILLMORE AND DAVID ANDEREGG, OF WESTERNVILLE,
NEW YORK.

PEA-HULLING MACHINE.

SPECIFICATION forming part of Letters Patent No. 728,759, dated May 19, 1903.

Application filed June 6, 1902. Serial No. 110,498. (No model.)

To all whom it may concern:

Be it known that we, WILLIAM F. PILLMORE and DAVID ANDEREGG, citizens of the United States, residing at Westernville, in the county of Oneida and State of New York, have invented a new and useful Pea-Hulling Machine, of which the following is a specification.

This invention relates to pea-hulling machines.

10 The object of the invention is to provide a machine which will in a thorough, feasible, practical, and expeditious manner effect hulling of the peas from the pods and the separation therefrom of the halm and vines. To effect this result, we provide a plurality of beater-drums disposed equidistantly around an ideal common axis, said beater-drums being provided with ribs which are so inclined as to impart propulsion of the material from 20 end to end of the space inclosed by said drums, the latter being in turn surrounded by a perforated drum or cylinder having lifting-ribs which coöperate with the beater-drums to propel, thresh, agitate, and separate the material operated upon. We also provide a feed opening or hopper in alinement with the space between the receiving ends of the beater-drums.

25 A further object of our invention is to extend the beater-drums at the discharge end beyond the inclosing cylinder to avoid entanglement of the vines and halm discharged from the machine with the operating parts thereof.

30 With these and other objects in view, as will appear as the nature of the invention is better understood, the same consists in the novel construction and combination of parts of a pea-hulling machine, as will be herein-40 after fully described and claimed.

35 In the accompanying drawings, forming a part of this specification, and in which like numerals of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof.

45 In the drawings, Figure 1 is a view in ver-

tical longitudinal section through a machine embodying the essential features of the present invention. Fig. 2 is a view in transverse section thereof, taken on the line 2 2, Fig. 1, 55 and looking in the direction of the arrow thereon.

55 Referring to the drawings, 1 designates generally the supporting-frame of the apparatus, which may be constructed in any preferred manner, preferably of wooden beams, such as are commonly employed in structures of this character. Supported for rotary movement upon guide-rollers 2, disposed, preferably, in pairs at the front and rear end of the frame, is an outer revolute, spokeless, shaftless, and open-ended drum or cylinder 3, which may be constructed of any suitable material and is provided with hulled-pea-escape openings 4, which are of a size to permit free escape of the peas, but to prevent passage therethrough of the halm. As herein shown this drum is circular in cross-section; but it is to be understood that, if preferred, it may be polygonal, and as this is common in structures 75 of this character detailed illustration thereof is deemed unnecessary. Projecting inward from the inner side of the drum is a series of longitudinally-disposed vine-elevating ribs 5, the number of the said ribs being 80 determined by the diameter of the drum and by the character of the vines to be operated upon. As herein shown, the ribs are associated with the cylinder by bolts or screws 6, which pass through exteriorly-disposed bat- 85 tens 7; but it is to be understood that no stress is to be laid to the particular manner of assembling the ribs with the cylinder, as various other ways of accomplishing this result may be adopted and still be within the 90 scope of the invention. The drum is driven in any preferred manner, preferably by a belt (not shown) passing around one end thereof.

95 Arranged within the drum and projecting at the discharge end thereof some distance therebeyond is a series of beater-drums 8 8^a 8^b—in this instance three—the axes of which are arranged on a line concentric with the drum 3, these beater-drums forming a circuit about the inner periphery of the outer or sep- 100 arating drum and being substantially equidistant therefrom and from each other. They

are all driven in the same direction as the outer drum and in any preferred manner, preferably through the medium of band-wheels 9, carried by the outer ends of the 5 shafts 10 of the said drums, the shafts being journaled in suitable bearings in cross-pieces at each end of the frame. The bodies of these drums may be constructed of any suitable material and are secured in any preferred 10 manner to heads 11, keyed or otherwise attached to the shafts 10. To the outer side of each of the beater-drums is affixed a series of beater-arms 12, which are by preference disposed at an angle with relation to the drum-shafts and overlap at an intermediate portion 15 of the drum, as clearly shown in Fig. 1.

13 designates a feed-chute which is disposed at the feed end of the drum, where it is suitably connected with the frame in such a position 20 that the vines fed to the machine shall be fed into the space between the beater-drums. A trough or receptacle 14 is suitably disposed beneath the outer drum for the reception of the shelled peas which pass from 25 the drum 3, from which said peas may be suitably fed to a place of deposit.

In practice the outer drum and the beater-drums are all driven in the same direction, as will be found indicated by arrows or darts 30 upon Fig. 2 of the drawings, said beater-drums being rotated at a relatively high rate of speed, as shown by the heavy darts.

The operation of the device is as follows: The pea-vines are fed into the chute or hopper 35 per 14, passing from thence into the space between the rapidly-rotating beater drums or cylinders. No care need be taken to feed the material slowly or evenly, inasmuch as as soon as a bunch of the vines enters the 40 space between the beater-drums it will be violently torn asunder and subjected to the threshing action of the beaters. When, as in the present instance, three beater-drums are used, the material fed between said drums 45 will be forced by the action of each drum in an outward direction toward the outer drum. A portion of the vines will pass into contact with said outer drum. The greater proportion, however, will adhere to the beaters and 50 be carried over or around the latter into the central space. It will also be seen that such portion of the vines as passes into contact with the inside of the outer drum will be elevated by the ribs of the latter until it reaches 55 a point even with or slightly above the drum 8. The tendency of the vines will be to drop upon said drum, and the tendency of the beaters upon the latter will be to carry the vines into the central space between the drums. 60 The tendency of the beaters upon the second drum 8^a to seize the vines and throw them outward against the inner wall of the outer drum will be counteracted by the beaters upon the third drum 8^b, the tendency of 65 which will be to throw the vines toward the first drum 8. It will thus be seen that the vines and pods by the combined action of

the several drums will be violently threshed and agitated and that the tendency of the combined action of the three inner drums 70 will be to retain the vines or halm between the said drums. It is not intended thereby to assert that the vines, pods, &c., are retained entirely in the space between the said beater-drums; but by far the larger proportion 75 is thus retained and will be progressively fed toward the discharge end of the machine, while the smaller and especially the heavier particles, including necessarily the shelled peas, will escape to the outer drum, through 80 the perforations of which they pass into the receiving-trough. Thus while the agitation to which the pea-vines is subjected is excessive from a standpoint of rapidity of action 85 the beating they receive does not result in any damage, such as a bruising or mashing of the peas, they being protected by the halm, from which they are readily separated and permitted to pass to the outer drum. The disposition of the ends of the beater-drum 90 with relation to the outer drum—i. e., their being projected beyond the outer drum—operates to prevent entanglement of the vines with parts of the machine.

It is preferred that the perforated shell of 95 the outer drum be made up in sections, by which arrangement should one or more become damaged or worn out ready repair may be accomplished.

While the machine of this invention is exceedingly simple of construction, it will be found thoroughly efficient and durable in use and will, with the output of the minimum of power, accomplish the maximum of work.

The precise construction of the different 105 parts of the apparatus herein shown is not defined, being immaterial, the broad underlying principle of the invention being rapid agitation and beating of the pea-vines by subjection to the action of an outer rotary drum 110 and a plurality of inner rotary drums.

Another and very essential distinguishing feature of our invention consists in the disposition within an outer drum of a plurality of beater-drums so disposed relatively to each 115 other as to form a central space into which the vines are fed and wherein they are mainly retained during their passage through the machine, the said beater-drums being rotated at a relatively high rate of speed in the direction of rotation of the outer drum, the latter thus coöperating with the beater-drums to elevate and to convey into the space between the latter such portions of vines and halm as will from time to time pass to the 120 inner space of the said outer drum.

Having thus fully described our invention, what we claim as new, and desire to secure by Letters Patent, is—

1. A machine for hulling green peas from 130 the vines, comprising a separating-drum supported revolubly and presenting an unobstructed interior, a plurality of beater-drums disposed longitudinally within and rotated in

the same direction as the separating-drum and distributed about its central or axial space, inclined or riffled ribs upon the said beater-drums, vine-lifting ribs upon the inside of the separating-drum, and means for feeding the vines into the central space between the beater-drums, which constitutes a conveyer-channel through which the vines mainly travel during their passage through

10 the machine.

2. In a machine for hulling green peas from the vines, the combination of an external drum adapted to revolve and to elevate the material, a plurality of interior beating and 15 conducting drums arranged inside thereof equidistantly from each other around the axial line of the outside drum and forming a central beating and conducting passage for the vines.

20 3. A machine for hulling green peas from the vines, comprising a separating-drum supported revolvably and presenting an unob-

structed interior, a plurality of beater-drums disposed longitudinally within and rotated in the same direction as the separating-drum 25 and distributed about its center or axial space, said beater-drums being arranged to project beyond the delivery end of the outer drum, inclined or riffled ribs upon said beater-drums, vine-lifting ribs upon the inside of the separating-drum, and means for feeding the vines into the central space between the beater-drums, which constitutes a conveyer-channel through which the vines mainly travel during their 30 passage through the machine.

35 In testimony that we claim the foregoing as our own we have hereto affixed our signatures in the presence of two witnesses.
